(57) **CLAIM**

The ornamental design for an allen wrench set holder, as shown and described.

DESCRIPTION

FIG. 1 is a front, top perspective view of an alien wrench set holder, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is an enlarged view of the area labeled 9 in FIG. 3. The dash-dash broken lines in the figures illustrate portions of the alien wrench set holder that form no part of the claimed design.

The dashed lines in the figures illustrate portions of the alien wrench set holder that form no part of the claimed design. The dot-dash-dot broken lines of the alien wrench set holder in FIG. 3 illustrate a boundary and cut line of the enlarged view in FIG. 9 and form no part of the claimed design.
